ICE BUCKET OR THE LIKE

Manuel S. Ziskin, University Heights, and Ralph B. Billig, Erieside, Ohio, assignors to Kromex Corporation, Cleveland, Ohio, a corporation of Ohio

Application September 1, 1948, Serial No. 148,405

Term of patent 14 years

(Cl. D44—1)

To all whom it may concern:

Be it known that we, Manuel S. Ziskin and Ralph B. Billig, citizens of the United States, residing at University Heights, county of Cuyahoga, and State of Ohio, and Erieside, county of Lake, State of Ohio, respectively, have invented a new, original, and ornamental Design for an Ice Bucket or the Like, of which the following is a specification, reference being had to the accompanying drawing, forming a part hereof.

Fig. 1 is a side elevational view of an ice bucket or the like, showing our new design;

Fig. 2 is a top plan view thereof.

We claim:

The ornamental design for an ice bucket or the like, substantially as shown.

MANUEL S. ZISKIN.
RALPH B. BILLIG.
